(57) **CLAIM**

The ornamental design for an electronic device housing, as shown.

DESCRIPTION

FIG. 1 is a perspective view of the front side of the electronic device housing.

FIG. 2 is a perspective view of the rear side of the electronic device housing.

FIG. 3 is a plan view of the front of the electronic device housing.

FIG. 4 is a plan view of the rear of the electronic device housing.

FIG. 5 is a side view of the electronic device housing illustrated with front side positioned upward.

FIG. 6 is a side view of the electronic device housing illustrated with the rear side positioned upward.

FIG. 7 is a side view of the electronic device housing illustrated positioned on its side; and,

FIG. 8 is a side view of the opposing side of the electronic device housing illustrated in FIG. 7.
